HOLDER FOR AN ARTIFICIAL AQUARIUM PLANT

Allan H. Willinger, New Rochelle, N.Y., assignor to
Metaframe Corporation, Maywood, N.J.

Filed Aug. 19, 1970, Ser. No. 24,583

Term of patent 14 years

Int. Cl. D30—99

U.S. Cl. D35—3

FIG. 1.

FIG. 2.

FIG. 3.

FIG. 4.

FIG. 5.

FIG. 6.

FIG. 1 is a front elevational view of a holder for an artificial aquarium plant, showing my new design;

FIG. 2 is a top plan view thereof;

FIG. 3 is a bottom plan view thereof;

FIG. 4 is a cross-section taken along line 4—4 of FIG. 2;

FIG. 5 is a cross-section taken along line 5—5 of FIG. 2; and

FIG. 6 is a side elevational view thereof.

I claim:

The ornamental design for a holder for an artificial aquarium plant, substantially as shown.
